DISPLAY DEVICE

Edward F. Schuerman, Cincinnati, Ohio

Application July 29, 1949, Serial No. 107,565

6 Claims. (Cl. 40—33)

1

This invention relates to display devices.

An object of the invention is to provide a display device which includes a plurality of duplicate display areas or panels each of which are mounted for independent or synchronized rotation about their respective axes.

Another object of the invention is to provide a display device having a plurality of duplicate panels each of which include opposed display portions constructed and arranged to accommodate changeable display indicia.

Still another object of the invention is to provide a display device having a plurality of duplicate panels each including opposed display portions, one of which is constructed to accommodate third dimensional display pieces, the other to accommodate two dimensional display pieces.

Still a further object of the invention is to provide a display device having the hereinabove described characteristics which includes means operable for selectively driving each of the panels from a common source and of automatically locking each panel in selected position after each driving sequence.

Still another object of the invention is to provide a display device provided with a plurality of duplicate display panels each of which include independently movable means for selectively controlling the disclosure of indicia peculiar to said panel.

Still a further object of the invention is to provide a display device having the hereinabove described characteristics which presents a pleasing attention-arresting overall appearance wherein the attention-arresting characteristics of the device are greatly enhanced by the movable features of various of its display panels.

Another object of the invention is to provide such a display device which may be effectively and advantageously used as a display media during periods of time when the various panels are stationary.

These and other objects are attained by the means described herein and as disclosed in the accompanying drawings, in which:

Fig. 1 is a front perspective view of a device embodying the teachings of the present invention.

Fig. 2 is a side view of the device of Fig. 1.

Fig. 3 is a side view of a modified form of device comprising a detail of the invention.

Fig. 4 is an end view of one of the display panels comprising a detail of the present invention.

Fig. 5 is an end view of a modified form of display panel.

2

Fig. 6 is a front view, partly in section, of the display panel of Fig. 5.

Fig. 7 is an end view of a pair of adjacent display panels illustrating their selectively driving means.

Fig. 8 is a schematic view of an electric circuit which may be utilized for controlling the operating characteristics of my device.

With reference to Figs. 1, 2 and 7, it will be noted that the device comprises, generally speaking, a housing 10, the front of which is open and comprises a plurality of similar or duplicate panels 12 each journaled for rotation about their own axis 14.

15 In the preferred embodiment of the invention each panel comprises opposed display portions 16 and 18, wherein one of said portions may be so constructed and arranged as to accommodate three dimensional display material, such as, by way of example, bottles 20, a radio set 22, stove 24 and any other type of third dimension object indicated generally in Fig. 7 by the numeral 26. The opposite portion 18 of each panel is preferably constructed in such a manner as to facilitate 20 the display of two dimensional indicia, such as, by way of example, placard 28 which may, if desired, bear any suitable legend, or other indicia.

With particular reference now to Fig. 7, it will be observed that each of panels 12 may be selectively driven or rotated from a common drive shaft 50 which may be driven by an electric motor 52, see Fig. 3.

Each of panels 12 may be journaled for rotation about axis 14 to which a pulley 54 may be secured in driving relationship. A gear 56 is slidably mounted on shaft 50, one for each panel. Each of said gears may be suitably keyed as at 58 to shaft 50, each gear being shiftable relative to shaft 50 by means of shifter arm or yoke 60 secured to and carried by the lower end of an actuator arm 62, the upper end of which may be operatively secured to a solenoid 64 in such a manner that energization of the solenoid will effect a lifting of actuator arm 62 and shifter arm 60 for effecting an engagement of gear 56 with a corresponding gear 66 to which a pulley 68 may be keyed, said last mentioned sets of pulleys and gears being suitably mounted and journaled for rotation about stub shafts 70 suitably secured relative to housing 10, in a manner not material to the instant disclosure. A latching arm 72 may be secured to and carried by actuator arm 62, said latching arm terminating in a detent 74 dimensioned to mesh with or between adjacent teeth of gear 66 for precluding 40 45 50 55

accidental or unintentional rotation of said gear.

Each set of pulleys 54 and 68 may be interconnected by means of an endless driving element 80.

The operating characteristics of the device are as follows:

With reference now to Figs. 7 and 8, it will be noted that suitable means, such as, by way of example, a sequence selector mechanism denoted generally by the numeral 90 may be provided for selectively energizing various of the solenoids 64, it being further understood that motor 52 will be energized each time any of the solenoids are energized. Energization of motor 52 will effect a rotation of drive shaft 50. Each of the various display panel gears 66 will be normally locked against rotation during those periods of time when their respective solenoids are de-energized during which time detents 74 engage their respective gears 66, wherefore each of the various panels will be locked in any desired, adjusted or preselected position.

When a solenoid 64 is energized, its associated actuator arm 62 will be elevated thereby disengaging detent 74 from associated gear 66 and simultaneously therewith gear 56 will be shifted upwardly into driving relationship with gear 66 whereby panel 12 will be rotated until its respective solenoid has been de-energized. If desired, the sequence selector may be entirely mechanical or if desired, it may be semi-automatic including a plurality of manually operable control elements 96 each of which provide manual control of motor 52 and one of the solenoids 64.

With reference now to Fig. 3, it will be noted that my driving mechanism enables me to dispose various of the display panels in varying relationships, thereby enhancing the overall utility of the device by enabling various of the panels to be locked in displaying position with reference to the eye-level of the average observer.

With reference now to Fig. 4, it will be noted that the indicia placard or panel 28 of Fig. 7 has been replaced by an endless belt 100 operating over spaced pulleys 162, one of which may be suitably driven for effecting travel of the endless belt thereby facilitating presentation of the information contained thereon. In this manner over twice the amount of information may be presented as can legibly be presented on a panel, such as 28 of Fig. 7.

With reference now to Figs. 5 and 6, it will be noted that a display placard or panel 120 has been mounted between spaced brackets 122 and that an endless belt 126 is disposed over laterally spaced rollers 128 and 130, wherein one of said rollers, such as by way of example, roller 130 may be driven by means of an electric motor 140 for causing said belt to move relative to indicia panel 120. A window or opening 142 may be provided in belt 126 for restricting the amount or area of placard 120 which is visible at any one time.

It should be understood that panels of the types disclosed in Figs. 4, 5 and 6 may be interchangeably associated with the device and with panels of Fig. 7.

If desired, access to the display media may be had thru a door, not illustrated, provided in the side or rear wall, of the housing, or the panels may be serviced from the front of the housing. Preferably, though not necessarily, I provide an arcuately shaped transparent hood-like member 136 over the three dimensional display portion of the panel.

It should be understood that if desired, both 75

the front and rear faces of each of panels 12 may be provided with third dimensional display devices, in which event arcuate hood-like members 136 would be provided on opposite faces of panels 12 whereby the overall contour of each of the display panels would be substantially cylindrical rather than semi-cylindrical.

It should be further observed that the instant device is quite useful even during those periods of time when various of the display panels are not being actuated. The overall characteristics of the device render it particularly adaptable for use in public places, such as, theater lobbies, department stores, stations and terminals of public utilities, the lobbies of auditoriums, and in fact, any place frequented by groups of people.

One of the uses contemplated by the device is to enable observers thereof to manually actuate certain accessible control elements, such as, by way of example, buttons 96 of the selector control unit, thereby enabling the observers to selectively actuate various of the display devices.

It should be understood that my device permits many and varied combinations of advertising indicia to be uniquely presented. If desired, the product disclosed in three dimensions on one side of a panel may have its opposing panel provided with pertinent information concerning it. Placard 28 of Fig. 1 may contain pertinent advertising information with reference to the subject matter of the three dimensional display 20 immediately above it. Likewise the rear face of the third dimensional display 22 immediately below the placard 28 may contain advertising copy with reference to the third dimensional material contained on the back or rear face of the next higher panel.

Another use to which my display device is particularly well adapted is for rendering available to the patrons of motion picture houses a sequential and current synopsis for persons arriving after the feature attraction has started. By mounting suitable synoptic résumés on placards 28, the patrons will be able to obtain a short résumé or synopsis of the action of the photoplay prior to their entrance into the theater.

Preferably such synoptic résumés will be officially released by the producers of the photoplay being shown, it being further understood that only one panel will be turned whereby to be visible to a spectator at any one time. That is, if the display device should comprise six display panels, such as illustrated in Fig. 3, only one would be provided, at any one time, with synoptic material.

In Fig. 3 the synoptic material would be visible in the second panel from the top, wherein the uppermost panel and the four immediately below the second panel would be utilized for displaying third dimensional advertising indicia.

The timing of the various synoptic panels would be controlled thru selector switch 90, or in some instances the actuation of the various panels could be controlled directly from the projection room of a photoplay house.

It should likewise be understood that the various types of panels, such as disclosed in Figs. 4, 5 and 6 may be utilized thereby increasing the amount of synoptic material which may be revealed to the patrons according to a definite predetermined sequence of operations.

The device of the instant invention is characterized by unusual attention-arresting characteristics which are emphasized by reason of

the "show-case" effect obtained by housing the third dimensional displays within or under the arcuately shaped transparent element 136.

What is claimed is:

1. A display device of the class described, comprising a plurality of display panels each mounted for rotation about their own axis, means operable for selectively rotating said panels from a common drive shaft including a rotatable drive shaft, a gear for each panel secured to said shaft for rotation therewith and axially movable thereon, a second gear for each panel, means operable for selectively establishing a driving connection between the first and second gears of each panel, means interconnecting each panel in driven relationship with its associated second gear, and means operable for rotating said drive shaft.

2. A display device of the class described, comprising a plurality of display panels each mounted for rotation about their own axis, means operable for selectively rotating said panels from a common drive shaft including a rotatable drive shaft, a gear for each panel secured to said shaft for rotation therewith and axially movable thereon, a second gear for each panel, means interconnecting each panel in driven relationship with its associated second gear, an electric motor for rotating said drive shaft, and means operable for selectively establishing a driving connection between the first and second gears of said panels and simultaneously energizing said electric motor.

3. A display device of the class described, comprising a plurality of display panels each mounted for rotation about their own axis, means operable for selectively rotating said panels from a common drive shaft, including a rotatable drive shaft, a gear for each panel secured to said shaft for rotation therewith and axially movable thereon, a second gear for each panel, means operable for selectively establishing a driving connection between the first and second gears of each panel and for automatically locking the second gear against rotation except when in driven connection with its associated first gear, means interconnecting each panel in driven relationship with its associated second gear, and means operable for rotating said drive shaft.

4. A display device including a housing having an open front, a plurality of display panels spanning said open front arranged in vertical alignment and mounted for independent rotation about their respective axes, a rotatable drive shaft, a plurality of gears secured to said shaft for rotation therewith and axially shiftable thereon, a shifting member for each of said gears, a solenoid for each shifting member, a plurality of

second gears, one for each display panel, means interconnecting each display panel in driven relation with its associated second gear, a detent for each second gear for normally precluding rotation thereof, means interconnecting each detent relative to an associated shifting member, means operable for selectively energizing said solenoids for moving their respective gear shifter members for simultaneously moving an axially shiftable gear along said drive shaft into driving engagement with an associated second gear and for releasing the detents from said second gear, and means operable for rotating said drive shaft incident to energization of any solenoid.

5. A display device of the character described comprising a plurality of display panels arranged in vertical alignment each journaled for rotation about their own axis, each panel including opposed display portions, means operable for selectively rotating said panels for presenting one or the other of their display portions to view, one of the display portions of each panel constructed and arranged to support third dimensional items mounted thereon, the other of said display portions constructed and arranged to receive two dimensional indicia bearing elements, and means associated with said last mentioned display portions for sequentially exposing to view portions of said two dimensional items.

20 6. A display device of the character described comprising a plurality of display panels arranged in vertical alignment each journaled for rotation about their own axis, each panel including opposed display portions, means operable for selectively rotating said panels for presenting one or the other of their display portions to view, one of the display portions of each panel constructed and arranged to support third dimensional items mounted thereon, the other of said display portions constructed and arranged to receive two dimensional indicia bearing elements, and means associated with said last mentioned display portions for sequentially exposing to view portions of said two dimensional items.

25 7. A display device of the character described comprising a plurality of display panels arranged in vertical alignment each journaled for rotation about their own axis, each panel including opposed display portions, means operable for selectively rotating said panels for presenting one or the other of their display portions to view, one of the display portions of each panel constructed and arranged to support third dimensional items mounted thereon, the other of said display portions constructed and arranged to receive two dimensional indicia bearing elements, and means associated with said last mentioned display portions for sequentially exposing to view portions of said two dimensional items.

30 8. A display device of the character described comprising a plurality of display panels arranged in vertical alignment each journaled for rotation about their own axis, each panel including opposed display portions, means operable for selectively rotating said panels for presenting one or the other of their display portions to view, one of the display portions of each panel constructed and arranged to support third dimensional items mounted thereon, the other of said display portions constructed and arranged to receive two dimensional indicia bearing elements, and means associated with said last mentioned display portions for sequentially exposing to view portions of said two dimensional items.

35 9. A display device of the character described comprising a plurality of display panels arranged in vertical alignment each journaled for rotation about their own axis, each panel including opposed display portions, means operable for selectively rotating said panels for presenting one or the other of their display portions to view, one of the display portions of each panel constructed and arranged to support third dimensional items mounted thereon, the other of said display portions including endless belt-type indicia bearing elements, and means operable for selectively actuating said elements.
